NONSHIMMYYING TROLLEY

Ralph T. Moore, Lakewood, Ohio, assignor to The American MonoRail Company, Cleveland, Ohio, a corporation of Ohio

Application December 23, 1944; Serial No. 569,447

4 Claims. (Cl. 105—156).

1

This invention relates generally to monorail conveyor trolleys and particularly to a trolley which has a tendency to "shimmy," that is, to move along a rail with the wheels inclined at varying angles to the edges of the rail or, in other words, to travel along a zigzag path.

Overhead trolleys, of the type in which a generally U-shaped yoke carries opposed, flanged wheels on axles at the open ends of the yoke, have a tendency to "shimmy" while traveling along a monorail track. Such shimmying action is permitted by the fact that the distance between the flanges of the pair of wheels is greater than the distance between the edges of the track flanges on which the wheels run. When the plane of the axes of the wheels is perpendicular to the rail the trolley may shift laterally until the flange of one wheel engages the side of the rail. Such movement is provided for and desired because the ends of adjoining rails are not always of exactly the same width or in exact alignment and such movement is necessary to permit free movement of the trolley from rail to rail.

The provision of space for such desired lateral movement permits the trolley to shift angularly, that is, to move the plane of the wheel axes out of a line perpendicular to the rail and thereby to incline the wheel flanges at an acute angle to the rail edges. When the wheels are so inclined, they run along a path inclined to the rail edges and eventually the leading part of the flange of one wheel or the trailing part of the flange of the other wheel contacts with the adjacent rail edge. When such contact occurs the axes are shifted and the wheels run along a path at an angle to the first path with eventual contact of wheel flange and rail edge which again shifts the axes. In this way the trolley traverses a zigzag path along the rail with resultant wear on the rail edges and on the flanged parts of the wheels and the formation of slivers of metal which frequently break loose and fall. Such slivers represent wear which should not occur and potential danger to workmen or work therebeneath which should be avoided. This oscillation of the trolley is commonly known as shimmy.

Altho this oscillating or shimmy problem has existed for many years and many attempts have been made to solve it, no one, to my knowledge, has solved it prior to my solution of it.

The present invention makes it possible to construct a trolley of the above described type which can shift laterally on a rail but which will not oscillate or shimmy to a material extent even when lightly loaded and traveling at high speeds.

2

and which can turn readily to conform to curves in the rail.

The present invention will be better understood by those skilled in the art from the following description and the drawings which accompany and form a part of this specification and in which

Fig. 1 is a diagrammatic plan view illustrating the shimmying action of trolleys running on a suspended track;

10 Fig. 2 is a fragmentary side elevational view of a pair of connected trolleys on the track of an overhead or suspended monorail system;

Fig. 3 is an enlarged fragmentary end elevational view, partly in section, taken on line 3—3 of Fig. 2;

Fig. 4 is a vertical sectional view taken on line 4—4 of Fig. 3;

Fig. 5 is a view similar to Fig. 4 but showing a single yoke and a spreader associated therewith;

20 Figs. 6, 7 and 8 are, respectively, top plan and side and end elevational views of the shimmy suppressor of Fig. 3;

Fig. 9 is a view similar to Fig. 3 but showing a modified form of shimmy suppressor;

25 Fig. 10 is a sectional view, partly in elevation, taken on line 10—10 of Fig. 9;

Fig. 11 is a view similar to Figs. 3 and 9 but showing another modified form of suppressor; and,

30 Fig. 12 is a sectional view taken on line 12—12 of Fig. 11.

In Fig. 1 the suspended rail of a monorail system is shown as consisting of a web 1 and flanges 2 extending outwardly therefrom and affording 35 surfaces or tracks on which wheels 3 of a trolley may run. As is shown in Figs. 1 and 3, the wheels 3 have flanges which are farther apart than the distance between the opposite edges of flanges 2. Accordingly, each pair of trolley

40 wheels 3 may shift laterally in either direction relative to web 1 of the rail until a wheel flange engages the adjacent edge of its track. When the plane of the axes of the wheels is substantially perpendicular to the web 1 of the rail, as is shown at the left end of Fig. 1, the trolley may shift laterally in that plane and thereby move freely from one end of a rail onto the abutting end of the next rail, even though the overall width of the flanges of the two rails is not exactly

45 the same, or the rail ends are not in exact alignment. Such lateral shifting, when the wheel axes are perpendicular to the rail web, is desirable. The other showings of wheels 3 in Fig. 1 illustrate positions the trolley wheels may and do assume when a trolley is moving along a rail. The

50

clearance between the flanges of the wheels and the edges of the flanges of the rail permit the trolley to shift angularly so that the plane of the axes of the wheels is not perpendicular to the web of the rail; in other words, so that the wheels are inclined at varying acute angles to the edges of the flanges or tracks. When the trolley shifts so that the plane of its wheel axes is not perpendicular to the web of the rail, the wheels run at an angle to the edges of the rail flanges until the flange on the leading side of one wheel, the wheel advanced by the shifting, engages the edge of its track flange or until the flange on the trailing side of the other wheel engages the edge of its track flanges. Then the friction or impact resulting from the engagement of one or both of these wheel flange portions with the track causes the trolley to shift in the opposite direction, whereupon the foregoing operation is repeated. This action is indicated on the right half of Fig. 1. This angular movement of the trolley wheels relative to the rail and the resultant oscillation of the yoke is commonly known as shimmying. It may occur under a variety of load and speed conditions but is perhaps most pronounced with high speeds and light loads. If the rate of such oscillation is slow it is not objectionable for it allows the rail to guide the wheels smoothly therewith and does not cause the wheels to wear the edges of the rails unduly or to apply impact forces to the rails. As the rate of oscillation increases, the rate of wear of the rail and the strength of the impact forces delivered to the rail increase and if the rate of oscillation becomes sufficiently high it may even prevent movement of the trolley along the rail because of the resulting escapement action.

Figs. 2, 3 and 5 show a typical overhead suspended monorail trolley embodying the present invention. Each U-shaped yoke 5, which preferably, but not necessarily, consists of two similarly shaped parts connected together by removable means such as bolts and nuts, has a body portion 6 which extends beneath flanges 2 of the rail and arms 7 which extend up past the flanges and carry axles 8 on which wheels 3 are rotatably mounted. The axes of axles 8 are in substantial alignment. Each wheel 3 has a tread surface 10 and a flange 11. The space between the flanges 11 of a pair of wheels in a yoke 5 is greater than the overall distance between the free edges of flanges 2 to permit the lateral shifting of the trolley relative to the rail as above mentioned. Two of yokes 5 are pivotally connected to a load bar 12. The bolt 12a depending from the mid-portion of bar 12 may be attached to another bar (not shown) similarly connected to another bar 12. Such an assembly is known as an 8-wheel trolley.

Fig. 4 shows one form of such pivotal connection between a yoke and load bar. In this figure the yoke 5 is shown as being provided with a recess open at its top and bottom and having an inner bottom surface which is a portion of a spherical surface. A thrust bearing 13 rests on the flat top of a washer 14, the lower surface of which is spherical to correspond to the inner bottom surface of the recess. The load bar 12 has a nut 15 preferably welded to its under surface and this nut rests on bearing 13. These several parts are held in assembled relation by bolt 16 which is threaded into nut 15 and extends thru bearing 13, washer 14 and yoke 5. Lubricant may be supplied thru fitting 17 to the recess in yoke 5 and to bearing 13 and washer 14 therein

to promote not only relative rotational, but angular, movement of the yoke and load bar.

When a single yoke trolley, such as that of Fig. 5, is being used instead of the two yoke combination of Fig. 2, much the same combination of parts may be employed as is shown in Fig. 4. In Fig. 5 the yoke 5 is similarly recessed and carries spherical washer 14 and thrust bearings 13. A nut 15a rests on bearing 13 and has screw threaded engagement with a bolt 16a which extends far enough below yoke 5 to have a spreader bar 18 mounted thereon to connect the yoke to other apparatus such as a pushing unit. One side of the head of bolt 16a is flattened to bear against a downward extension 19 of bar 18 to prevent turning of bolt 16a relative to yoke 5.

Means for suppressing shimmy is shown in Figs. 2 to 12 inclusive and having curved upper surfaces. The form of shimmy suppressor shown in Figs. 2 to 8 inclusive comprises a spring 20 which has a wide body portion 21 attached to the top of load bar 12 or to nut 15a, as the case may be, and wings 22 which extend downwardly and bear on lugs 23 secured to the yoke 5. As will be better understood by reference to Fig. 8, each wing 22 is high in the center and is curved downwardly therefrom on each side to form fingers 24. The lugs 23 engage against the under surface of the high part of wings 22 when the wheel axes are at right angles to the rail; and when there is any tendency for the yoke to shift so that the wheels are acutely inclined to the edges of the rail flanges 2, the lugs 23 will be forced against fingers 24 of the suppressor and will deform them somewhat. The pressure of the spring and the resulting friction will retard any shifting of the yoke relative to the rail.

In the modification shown in Figs. 9 and 10 the shimmy suppressing means comprises a spring 30. This spring engages ledges 31 on the yoke and rests on the top of nut 15a. The spring 30 is normally distorted by its engagement with nut 15a and ledges 31 so that it maintains its position on and exerts pressure against nut 15a at all times and thereby tends to retard relative rotation of the nut and yoke.

Another modified form of the suppressor is shown in Figs. 11 and 12 respectively where the yoke 5 is provided with opposed recesses 40 in which springs 41 are mounted to surround the stems 42 of shoes 43 whose inner surfaces are fragments of cylinders engaging the outer cylindrical surface of a nut 15a similar to that shown in Fig. 5 or nut 15 similar to that shown in Fig. 4 but somewhat longer in vertical length. The springs 41 serve to press shoes 43 against the nut and thereby retard periodic pivoting action of the yoke relative to the nut. The nut 15a of Fig. 11 is also similar to the nut 15a of Fig. 9 and is similarly attached to the depending bolt (unnumbered) and, as is indicated in dotted lines in Fig. 11, the nut 15a is supported on roller bearings and a spherical washer like washer 14 of Figs. 4 and 5 also shown in cross-section in Fig. 9.

It might be supposed that the anti-friction means between the trolley yokes and load bars or spreader bars, as shown in Figs. 4 and 5, would permit excessive shimmying action but such is not the case. I have discovered that shimmy occurs under certain conditions when these pivotal connections have high friction including poor bearings. The present invention, as embodied in the illustrated devices and comprising anti-friction pivotal connections between the yokes 5 and the load bars or load-supporting members

and the suppressors has been found to be capable of preventing substantially all shimmy action in unloaded or lightly loaded trolleys travelling at speeds of several hundred feet per minute and yet the trolleys move freely around curves when heavily loaded without any appreciable increase in resistance to the pivoting of the yokes relative to the load bars. The suppressors exert enough force to substantially prevent sudden changes in angularity of the wheels and rapidly reciprocating changes due to shimmy producing causes but do not exert so much force as to materially resist the turning effect which is exerted by the wheels engaging a curved track. Thus the trolley is substantially free from shimmy but can follow curves quite readily.

Trolleys embodying the present invention have much greater lengths of service life than the prior trolleys and wear the rails to a much less extent. These advantages are traceable to the substantial absence of shimmy and to the presence of the low frictional bearing between the yoke and the load carrying member.

Having thus described my invention so that others skilled in the art may be able to understand and practice the same, I state that what I desire to secure by Letters Patent is defined in what is claimed.

What is claimed is:

1. A trolley for a suspended rail having opposed, outwardly extending flanges constituting tracks for trolley wheels, said trolley comprising a yoke member having opposed wheels to run on said tracks and flanges engageable with the sides of said tracks, a load carrying member rotatably connected to said yoke member and deformable means connected to one of said members and frictionally engaging and being initially deformed by the other of said members for impeding relative rotation of said members and sudden changes in angularity of the yoke member and wheels to said rail.

2. A trolley for a suspended rail having opposed, outwardly extending flanges constituting wheel tracks, said trolley comprising a yoke member having opposed wheels to run on said tracks and flanges engageable with the edges of said tracks, a load carrying member rotatably connected to said yoke member and initially stressed sheet metal spring means carried by the yoke

50

member and frictionally engaging said load member for exerting pressure on the latter member and thereby retarding sudden changes in the angularity of the yoke member and wheels to said rail.

3. A trolley for a suspended rail having opposed, outwardly extending flanges constituting tracks for trolley wheels, said trolley comprising a yoke member having opposed wheels to run on said tracks and flanges engageable with the edges of said tracks, a load carrying member rotatably connected to said yoke member and resilient means carried by said yoke member and initially stressed to exert pressure on said load carrying member to retard relative rotation of the said members and sudden changes in the angularity of the yoke member and wheels to said rail.
4. A trolley for a suspended rail having opposed, outwardly extending flanges constituting tracks for trolley wheels, said trolley comprising a yoke member having opposed wheels to run on said tracks and flanges engageable with the edges of said tracks, a load carrying member, antifriction means between said members, said means including a part having a partial spherical surface, engageable with a correspondingly shaped surface on said yoke member, and initially tensioned means carried by one of said members and initially applying frictional pressure to the other of said members for retarding relative rotation of said members and sudden changes in angularity of the yoke member and wheels relative to said rail.
